UNITED STATES PATENT OFFICE.

JOSEF HURTIG, OF ROCHESTER, NEW YORK.

ELECTRICALLY-DRIVEN SPINDLE.

1,327,160.

Specification of Letters Patent.

Patented Jan. 6, 1920.

Application filed January 8, 1919. Serial No. 270,145.

To all whom it may concern:

Be it known that I, JOSEF HURTIG, a subject of the Kingdom of Sweden, and a resident of the city of Rochester, State of New York, (whose post-office address is corner of Gibbs and Grove streets,) have invented new and useful Improvements in Electrically-Driven Spindles, of which the following is a specification.

10 This invention relates to a method of applying an electric motor to fast revolving spindles such as are used in wood working and other similar machines, and it consists mainly in providing for the easy removal 15 of the spindle and accompanying motor from its supporting yoke, and furthermore in means of concentrically clamping the motor frame and the bearings of the spindle into the supporting yoke: also other suitable 20 means for rendering the invention fully operative.

In the accompanying drawings, Figure 1, is a front elevation of my device and Fig. 2 is a plan view of the same. Fig. 3 is a central sectional elevation. Fig. 4 is a sectional outline showing the spindle, its main bearing and the surrounding sleeve partly withdrawn from its working position in the yoke. Fig. 5 is a section at X, Fig. 3, showing the attachment of the motor frame or stator to the yoke. Fig. 6 is a central section of a ball bearing substitute for the main bearing shown in Fig. 3. A is the supporting housing or yoke in which the motor frame or stator B and the spindle bearings C and D are mounted. The spindle bearings may be of any suitable type, such as C which has a conical bore, or D which shows a ball or roller bearing. E is the spindle 40 to which the rotor F is securely attached.

The above refers to a well known construction, but my invention relates to novel details in the construction and assembling of the parts as described below.

45 By reference to Figs. 3 and 4, it will be seen that the yoke A is bored through longitudinally to form housings for the bearings C and D, and the stator B as shown at 3, 4 and 5, Fig. 4. In the housing section 3 is 50 fitted the sleeve 2, which surrounds and carries the main bearing C. To the underside of this sleeve the cap 6 is secured which forms an oil reservoir, and below this are located the oil guard 7 and the rotor F, both 55 attached to the spindle E. The bearing C,

whether of the conical type shown in Fig. 3, or the ball or roller type seen in Fig. 6, requires circulating channels for oil which is lifted to the journals by wicks 15 or by some form of oil circulator 16 for the ball bearings: for this purpose I provide return channels 17 which communicate at their lower end with the oil well or chamber 6: thus oil which is carried up by the wicks or circulator is kept in constant circulation through 60 the oil chamber and passages.

The object of the sleeve 2 surrounding the bearing C is to enlarge the opening 3 sufficiently to permit the removal of the motor F lengthwise of the yoke A, as indicated in 70 Fig. 4 where the spindle and attached parts are shown partly withdrawn from the yoke. By this means it is a simple matter to detach the lower bearing D and remove the spindle and rotor whenever it is required 75 for repairs or examination; the outside diameter of the sleeve 2 is such that the stator B can also be removed through the bore 3 of the housing; thus it is plain that in the fitting up and assembling of the machine, 80 much time can be saved by this method of removal and replacement of parts.

The sleeve 2 is preferably cut through on one side as at 8, Fig. 2, for compression as hereinafter described. For the purpose of 85 clamping the sleeve 2 and stator B firmly into the yoke A, the clamping sections 10 and 11, Fig. 1, are cut through on one side as at 12, Figs. 2 and 5, and clamp bolts 14 are located to draw the joint down and thereby pinch the sleeve and stator tightly 90 into the bores provided for them, which also brings them into exact alinement and concentricity with each other and the spindle: the sleeve 2 is also compressed a trifle by 95 this clamping action, thus clamping the bearing C in position at the same time, all these parts being thus kept in exact alinement as above mentioned: the same is true of the bearing D, the socket for which is 100 bored at the same time as those for the stator and sleeve 2.

What I claim as my invention and desire to secure by Letters Patent is:

1. A high speed spindle having the rotor 105 of a motor securely attached to it, a bearing contiguous to the rotor, a removable sleeve carrying the bearing, a sustaining yoke or housing into which the removable sleeve and the stator of the motor are fitted, whereby 110

the spindle, the motor, the removable sleeve, the main bearing and other attached parts can be readily removed.

2. The combination with a supporting yoke or housing provided with two separated cylindrical bearing surfaces adapted to be independently contracted and expanded, of a cylindrical motor stator adapted to be clamped in one of said bearings, a motor rotor, a spindle carrying the rotor, and a removable sleeve in which said spindle is rotatably mounted having an external diameter at least equal to that of the stator and adapted to be clamped in the other bearing of the housing.
3. A high speed spindle having an electric rotor attached, a main bearing contiguous thereto, a removable sleeve surrounding said bearing, a yoke or housing fitted to receive

said sleeve and the stator of the motor, and means for clamping the bearing, the sleeve and the motor firmly into said housing and concentrically to each other.

4. A high speed spindle having a motor rotor attached, a bearing or bearings contiguous thereto, a removable sleeve surrounding said bearing, a supporting yoke or housing provided with cylindrical clamping sections embracing the sleeve and the motor stator, said sections being cut (or split) through on one side and provided with bolts to clamp the parts firmly and concentrically in the housing.

JOSEF HURTIG.
